UNITED STATES PATENT OFFICE.

THOMAS W. JESTER, OF BAINBRIDGE, GEORGIA.

WRENCH.

No. 823,870.

Specification of Letters Patent.

Patented June 19, 1906.

Application filed August 5, 1905. Serial No. 272,866.

To all whom it may concern:

Be it known that I, THOMAS W. JESTER, a citizen of the United States, residing at Bainbridge, in the county of Decatur and State of Georgia, have invented new and useful Improvements in Wrenches, of which the following is a specification.

The invention relates to an improvement in wrenches, and particularly of the type known as "pipe-wrenches."

The main object of the present invention is the production in a wrench of the class described of means adapted to automatically adjust or tighten the wrench during its operative engagement with the pipe, whereby positive action of the wrench is assured and slipping during use wholly obviated.

The preferred details of construction will be described in the following specification, reference being had particularly to the accompanying drawings, wherein—

Figure 1 is a view in side elevation of a wrench constructed in accordance with my invention. Fig. 2 is a similar view, the movable jaw of the wrench being shown in vertical section. Fig. 3 is a vertical section through the sliding jaw. Fig. 4 is a transverse section illustrating the parts in coöperative relation.

Referring to the drawings, my improved wrench comprises the usual shank 1, provided at one end with a handle 2 and at the opposite end with the ordinary fixed jaw 3, preferably formed with serrations or teeth 4 on its operative face, as is usual in wrenches of this type.

5 represents what I term the "sliding jaw," preferably comprising a hollow body designed to embrace the shank 1, being preferably provided adjacent the side faces of the shank with vertically-arranged ribs 6, designed for coöperative engagement with longitudinal channels 7, formed in the adjacent faces of the shank, whereby the sliding jaw is 45 positively guided in vertical movement.

The forward face of the shank 1 is formed with a series of transversely-arranged ribs or teeth 8, and within the sliding jaw is mounted a cog-pinion 9, positioned to coöperate 50 and intermesh at all times with the teeth 8. The pinion 9 is preferably mounted about centrally of the movable jaw, being supported upon a pin 10, extending through and headed beyond the side walls of said movable 55 jaw.

In connection with the movable jaw I ar-

range what I term a "moving pipe-section" 11, comprising a rectangular block formed at opposite points on its side edges with longitudinally-arranged grooves or channels 12, 60 designed to receive ribs 13, projecting inwardly from the upper ends of the side edges of the movable jaw, it being understood that the movable pipe-section is thus mounted for sliding movement transverse the length of 65 the movable jaw and at the upper end of the latter, said pipe-section being formed on its upper side, or that face adjacent the operative face of the fixed jaw 3, with a series of stepped offsets 14, designed to coöperate 70 with the teeth 4 on the fixed jaw to grip the pipe. The movable pipe-section is formed 75 with a longitudinal bore 15, in which is housed a coil-spring 16, terminally secured at one end to the rear wall of the bore and at 80 the opposite end to a projection 17, extending from the front wall of the fixed jaw, as clearly shown in Fig. 4. A projection or tooth 18 depends from the under side of the movable pipe-section and within the movable jaw, said tooth being of a size to coöperate 85 with the teeth on the pinion 9, but normally held out of engagement with said pinion through the position of the movable pipe-section under tension of the spring 16. An 90 adjusting-arm 19 is slidably mounted near the lower end of the movable jaw, being arranged at one end for engagement with the teeth 8 on the shank 1 and at the opposite end projecting through the forward wall of 95 the movable jaw and terminally provided with a handle 20 therebeyond. A spring 21, connected to the arm 19 and to the forward wall of the movable jaw within said jaw, serves to normally maintain said arm in engagement with the teeth 8, whereby to secure the movable jaw in adjusted relation to the fixed jaw.

Assuming the parts constructed and arranged as described, the operation of my improved wrench is as follows: By suitable operation of the adjusting-arm 19 the movable jaw of the wrench is manually adjusted to embrace the pipe to be turned. In movement of the wrench to turn the pipe the 100 movable pipe-section 11 will, through the pressure exerted, be forced toward the shank 1 of the wrench, which movement of said section 11 causes its tooth 18 to engage the teeth of the pinion 9, tending to force said pinion in a direction which, through the co-operation of said pinion 9 with the teeth 8

- of the shank 1, tends to move the sliding jaw toward the fixed jaw, so that the greater the pressure exerted upon the pipe the more securely the pipe is embraced between the sliding and fixed jaws. It will thus be noted that as soon as pressure is exerted upon the wrench-handle to turn the pipe a continuous and uninterrupted tightening of the wrench on the pipe is automatically maintained.
- 5 10 The operation of the parts to adjust the sliding jaw is readily and quickly accomplished through proper movement of the arm 20, the sliding jaw being guided in its adjusting movement through the coöperation of the ribs 6 and grooves 7. The spring 16 operates to return the sliding pipe-section to normal position upon release of the pressure incident to the use of the wrench, so that said sliding section is always in position for the described 15 movement necessary to tighten the parts when using the wrench.
- Having thus described my invention, what I claim as new, and desire to secure by Letters Patent, is—
- 20 25 1. A wrench comprising a fixed jaw, a movable jaw, a sliding section carried by the jaw, and means other than said section and adapted for operation thereby to force the sliding jaw toward the fixed jaw in the operation of the wrench.
- 30 35 2. A wrench comprising a fixed jaw and a movable jaw, movable means carried by said latter jaw to coöperate with the fixed jaw, and means other than the movable means adapted to force said movable jaw toward the fixed jaw in the operation of the movable means in one direction.
- 40 45 3. A wrench comprising a fixed jaw, a movable jaw, means carried by said latter jaw to feed the movable jaw to and from the fixed jaw, and means carried by the movable jaw to coöperate with said feeding means to force the movable jaw toward the fixed jaw in the operation of the wrench.
- 50 55 4. A wrench comprising a shank formed with a fixed jaw, a sliding jaw movable longitudinally of the shank, a movable section carried by said sliding jaw and arranged to coöperate with the fixed jaw, a gear-pinion mounted in the sliding jaw arranged to coöperate with the teeth formed with the shank, and means carried by the movable section to engage and move said pinion in the use of the wrench.
- 60 65 5. A wrench comprising a shank formed with a fixed jaw, a movable jaw embracing the shank, the forward face of the shank being formed with teeth, a gear-pinion mounted within the movable jaw and arranged to engage the teeth on the shank, a movable section carried by the movable jaw and adapted to coöperate with the fixed jaw, and a tooth depending from said section and adapted on movement of the section to engage and operate the pinion.

6. A wrench comprising a shank formed with a fixed jaw, a movable jaw embracing the shank, the forward face of the shank being formed with teeth, a gear-pinion mounted within the movable jaw and arranged to engage the teeth on the shank, a movable section carried by the movable jaw and adapted to coöperate with the fixed jaw, and a tooth depending from said section and adapted on movement of the section to engage and operate the pinion, and means for returning said movable section to normal position.

7. A wrench comprising a shank formed with a fixed jaw, a movable jaw embracing the shank, the forward face of the shank being formed with teeth, a gear-pinion mounted within the movable jaw and arranged to engage the teeth on the shank, a movable section carried by the movable jaw and adapted to coöperate with the fixed jaw, and a tooth depending from said section and adapted on movement of the section to engage and operate the pinion, and means for securing said movable jaw in adjusted position with relation to the fixed jaw.

8. A wrench comprising a shank formed with a fixed jaw, a movable jaw embracing the shank, the forward face of the shank being formed with teeth, a gear-pinion mounted within the movable jaw and arranged to engage the teeth on the shank, a movable section carried by the movable jaw and adapted to coöperate with the fixed jaw, and a tooth depending from said section and adapted on movement of the section to engage and operate the pinion, and an arm movably mounted in the movable jaw and adapted to coöperate with the teeth on the shank.

9. A wrench comprising a shank formed with a fixed jaw, a movable jaw embracing the shank, the forward face of the shank being formed with teeth, a gear-pinion mounted within the movable jaw and arranged to engage the teeth on the shank, a movable section carried by the movable jaw and adapted to coöperate with the fixed jaw, and a tooth depending from said section and adapted on movement of the section to engage and operate the pinion, and a spring housed within the movable section and terminally connected to said section and to the movable jaw.

10. A wrench comprising a shank having a fixed jaw, a sliding jaw movable on the shank, feeding means carried by the sliding jaw to coöperate with the shank, and means independent of the feeding means and carried by the sliding jaw, said latter means being adapted to operate the feeding means in the use of the wrench.

In testimony whereof I affix my signature in presence of two witnesses.
